United States Patent Office.

MILTON V. NOBLES, OF ELMIRA, NEW YORK.

Letters Patent No. 101,652, dated April 5, 1870

GRIDIRON-CASE.

The Schedule referred to in these Letters Patent and making part of the same.

To all whom it may concern:

Be it known that I, MILTON V. NOBLES, of Elmira, in the county of Chemung and State of New York, have invented a new and valuable Improvement in Gridiron-Cases; and I do hereby declare that the following is a full, clear, and exact description of the construction and operation of the same, reference being had to the annexed drawing making a part of this specification, and to the letters and figures of reference marked thereon.

Figure 1 of the drawing is a representation of a vertical section of my gridiron case.

Figure 2 is a view of my gridiron adapted for operation in said case; and

Figure 3 is an external view of said case, showing the mode of connection between the sections thereof.

My invention relates to household utensils, and

It consists in a case of novel construction and form, adapted for use in conjunction with a certain gridiron for which Letters Patent were allowed me on the 29th day of October, 1869.

My gridiron-case is constructed in two sections, marked respectively A and B, on the drawings.

The section A has a handle marked C attached to its top, and its bottom is enlarged in such manner as to shut over the upper edge or rim of section B, and thereby be attachable to or removable from said section B at will.

The letters a represent small ears or lugs in which the sliding bolt c is held and operated.

I also make openings in said section A marked d, (one on each side thereof,) to provide for holding and operating the gridiron, as hereinafter mentioned.

I sometimes make the extreme top of section B of mica, or I may make an opening therein, to be closed at will by a sliding door, to enable the operator to ex-

amine the interior of the case without removing or disconnecting one section from the other.

Section B is constructed in the form shown on the drawings, and is open at both ends. Being substantially of the shape of an inverted cone, its lower end is adapted to fit in pot-holes of various sizes from six to ten inches in diameter without the aid of rimmers.

The upper end of this section B is arranged to fit inside the lower end of a section A, and I make a shoulder, s, to form a rest or support for section A when the two sections are united.

The letter e represents a lug or ear on section B, adapted to receive the bolt c, and in conjunction with lugs a to hold the two sections firmly together, when desirable so to do.

The letter H represents my gridiron, above referred to, a full description of which is given in my specification accompanying my application for Letters Patent, and to which specification I hereby refer.

The mode of adjusting my gridiron in the case is shown on fig. 1 of the drawing, and when so adjusted it may be rotated at will, the object being to bring each side of the article being beveled or toasted to the fire as often and as long as may be necessary or desirable.

The handle C is sometimes filled with mortar of gypsum.

What I claim as my invention is—

The case for gridirons herein described, having sections A and B, lugs a and e, bolt c, and openings d, constructed and arranged substantially as specified.

M. V. NOBLES.
